C. J. HUNT

UNDERGARMENT RETAINING DEVICE

Filed April 22, 1924

Inventor
CORNELIA J. HUNT,

By *Murray Edgell*

Attorneys

Patented Mar. 10, 1925.

UNITED STATES PATENT OFFICE.

CORNELIA J. HUNT, OF CINCINNATI, OHIO.

UNDERGARMENT RETAINING DEVICE.

Application filed April 22, 1924. Serial No. 708,311.

To all whom it may concern:

Be it known that I, CORNELIA J. HUNT, a citizen of the United States of America, and a resident of Cincinnati, in the county of Hamilton and State of Ohio, have invented a new and useful Improvement in an Undergarment Retaining Device, of which the following is a specification.

My invention relates to a device for retaining shoulder straps of women's under garments in position upon the shoulder.

An object of my invention is to provide a simple and efficient device for the purpose stated.

Another object of my invention is to provide a device that is readily interchangeable.

These and other objects are attained by the means described herein, and disclosed in the accompanying drawings, in which—

Fig. 1 is a fragmental view of a device embodying my invention applied to a garment.

Fig. 2 is a view of a device embodying my invention showing the device in the extended form.

Fig. 3 is a view of the device shown in Fig. 2 showing same in a folded, contracted, or operative position.

The device of my invention comprises an elongated strip 10, preferably of some flexible material, such as tape, provided at its one end 11 with an element 12 of a snap fastener or snap button adapted to engage the complementary fastening device 13 carried by the strip 10 intermediate its ends, and near the center of the strip 10. The end 14 of the strip 10 is provided with a pair of apertures 15 and 16 that are preferably stitched about their edges so as to preclude ravelling of the material comprising the strip 10. An attachment means 17, for example as shown herein, a safety pin,

is adapted to be projected through the apertures 15 and 16 and to secure the strip 10 upon the inner surface of a garment 18. The garment 18 is in the nature of a shirt waist that serves to substantially cover the shoulders of a wearer. The garment 18 therefore provides a substantial securing means for the strip 10 so that when the straps 19 of an under garment such as a brassière or the like, are received between the loop or eye 20 formed by bending the strip 10 upon itself for engaging the snap fastened elements 12 and 13, the straps 19 are positively precluded from slipping over the shoulders of a wearer.

It is obvious that the strips 10 are readily changed from one garment 18 to another similar garment and that straps 19 may be readily secured in the loop 20 and as readily released from the garment and retaining device 10.

What I claim is:

As a new article of manufacture, a shoulder strap retaining device comprising an elongated strip, the strip having a snap fastener element at its one end and having apertures at its other end, a second snap fastener element carried by the strip intermediate the first mentioned snap fastener element and the second end of the strip, the second mentioned snap fastener element being adapted to co-operate with the first mentioned snap fastener element for retaining part of the strip in a loop formation, and a safety pin extending through the apertures provided in the strip, and adapted to engage a garment for affixing the strip to the garment.

In testimony whereof I have hereunto subscribed my name this 11th day of April, 1924.

CORNELIA J. HUNT.
